United States Patent Office

Des. 188,799
Patented Sept. 13, 1960

188,799

GAME TABLE

Tony Jenovino, 2640 Azalea Road, Sacramento, Calif.

Filed Sept. 15, 1958, Ser. No. 52,656

Term of patent 14 years

(Cl. D34—5)

F/G. 1

FIG. 2

FIG. 3

The essential features of my design reside in the portions shown in full line.

1 claim:

The ornamental design for a game table, as shown and described.
